UNITED STATES PATENT OFFICE.

ORVEL JAY CRAIG, OF MINNEAPOLIS, MINNESOTA.

FASTENING DEVICE.

Application filed June 4, 1925. Serial No. 34,850.

My invention has for its object to provide improved means for attaching a tag or ticket to a garment or other object by means of a button on said garment or object, and to 5 this end it consists of the novel construction hereinafter described and defined in the claims.

In the accompanying drawings, which illustrate the invention, like characters indicate like parts throughout the several views.

Referring to the drawings:

Fig. 1 is a face view of a tag having the invention embodied therein;

Figs. 2 to 4, inclusive, are views showing 15 different steps in attaching the tag to a garment by means of a button thereon;

Fig. 5 is a view principally in section taken on the line 5—5 of Fig. 3; and

Fig. 6 is a view corresponding to Fig. 1 20 but showing a slight modification.

The numeral 5 indicates what may be assumed to be two parts of a garment connected by a button 7. This button 7 is attached to the under part of the garment by 25 a thread which is worked back and forth to form a shank 8 for said button and which button is inserted through a button hole 9 in the upper part of the garment 6.

As is illustrated, the invention is embodied in a price tag or ticket 10 formed from 30 a relatively stiff piece of paper or card board. Said invention consists of a T-shaped button passage 11 formed in the tag 10 near one end thereof. The head of the 35 passage 11 is in the form of a slit 12 and the stem thereof is in the form of a slot 13. Said slot 13 is of such width as to freely receive the button shank 8 when the button 7 is inserted through the slit 12. The slit 40 12 has a width, if any, materially less than that of the button shank 8 and prevents said shank from entering said slit by a movement of the tag 10. By this construction, the button shank 8 always remains in the 45 slot 13 and keeps the tag 10 transversely centered in respect to the button 7.

The formation of the T-shaped button passage 11 leaves two flaps 14 under the slit 12 and at the sides of the slot 13. Both 50 the slit 12 and slot 13 must each have a length that is greater than the diameter of the button 7.

To attach the tag 10 to the garment 6, by 55 means of its button 7, it is only necessary to press the tag 10, above the button passage

14, onto the button 7 to bow the respective portion of said tag and thereby expose the flaps 14 to the under edge of the button 7. Then by moving the tag 10 endwise, in the direction of the arrow marked thereon in Fig. 2, the flaps 14 will be caused to pass under the button 7 and said button to enter the slit 12 and its shank 8 to enter the slot 13. A further endwise movement of the tag 10, in the same direction as indicated by the arrow marked thereon in Fig. 3, will carry the button 7 completely through the slit 12 and its shank 8 to the lower end of the slot 13. Then by giving the tag 10 a reverse endwise movement, as indicated by the arrow marked thereon in Fig. 4, said tag 10 is so positioned that the button shank 8 is at the upper end of the slot 13 and said tag properly positioned and held by the button 7. As the slit 12 is of a width materially less than 70 the diameter of the button shank 8, said shank will always remain in the slot 13 and thereby keep the tag 10 transversely centered in respect to the button 7.

To detach the tag 10 from the button 7, 80 said tag is first moved into a position shown in Fig. 3 and then said tag given a reverse endwise movement, and at the same time said tag is lifted to engage the button 7 and thereby bow the flaps 14 downward to permit the button 7 to pass out of the slit 12 and its shank 8 out of the slot 13.

Referring now to the modification shown in Fig. 6, the tag 15 has a button passage 16 identical with the button passage 11 with the exception that the slit 17 has at its ends 90 extensions 18 which project in the same direction as the slot 19, but as shown are in diverging relation. These extensions 18 may vary in length and even if they were as long as the slot 19, the button passage 16 could be still termed T-shaped in form. By providing these slots 17 with the extension 18, greater flexibility is given to the flaps 20. These extensions 18 also make it possible 100 to insert a much thicker button through the slit 17 than through the slit 12.

From the above description, it is evident that the tags 10 and 15 may be very easily and quickly attached to a garment by means of one of its buttons, or removed therefrom by the use of only one hand and a slight pressure.

What I claim is:

1. A tag having a T-shaped button-receiving

ing passage, the stem of which is in the form of a slot adapted to receive the shank of a button, the length of said slot being such that when the tag is attached to a button and positioned with the shank of the button at the bottom of said slot, the upper edge of the button will be below the head of said

passage, the head of the passage having at its ends downturned extensions.

2. The structure defined in claim 1 in which said downturned extensions are in diverging relation.

In testimony whereof I affix my signature.

ORVEL JAY CRAIG.
